UNITED STATES PATENT OFFICE.

TORSTEN SCHILLBERG, OF GLASGOW, SCOTLAND.

MASSAGE APPLIANCE.

SPECIFICATION forming part of Letters Patent No. 723,735, dated March 24, 1903.

Application filed July 8, 1902. Serial No. 114,717. (No model.)

To all whom it may concern:

Be it known that I, TORSTEN SCHILLBERG, masseur, a subject of the King of Sweden and Norway, and a resident of 353 Bath street, 5 Glasgow, Scotland, have invented a Massage Appliance Chiefly for the Self-Treatment of the Scalp, of which the following is a specification.

This invention relates to a massage appliance chiefly for the self-treatment of the scalp.

The appliance consists of a pair of handles A, which may be of wood or other material, with circular or other-shaped ends a, as shown in the perspective view, Figure 1, into which 15 hollow conical rubbers B, preferably of india-rubber, are fixed. The two handles are connected together by means of the link C and eyelets c, which are screwed into the tops of the handles. The patient takes a handle in 20 each hand, with his head between the rubbers, the linking of the handles together enabling the patient to give any required pressure upon the scalp without exertion, the head being gripped or wedged between the two rubbers, so that, the scalp being gripped by the 25 rubbers, any desired friction movement can be given between the scalp and the skull for the purpose of increasing the circulation of the blood in the scalp, by means of which the 30 scalp gets nourished and the hair growth is strengthened.

As shown in Fig. 2, the rubbers B are inserted within the wood a of the handle, being retained by means of the ring-plate a', secured 35 by screws a''. The hollow of the rubbers is preferably ribbed, as shown, to assist in the rubber gripping the scalp in the giving of the required friction motion of the scalp on the skull, the hollow of the rubbers also tending 40 to give adherence of the rubbers to the scalp by suction.

By means of this appliance the patient can

efficiently massage his own scalp and without exertion.

If desired, the handles may be unhooked 45 and the one rubber only used.

I do not limit myself to the precise shape of the handles or of the rubbers nor to the particular method of connecting the two handles together, as the same may be varied. 50

I claim—

1. A massage appliance consisting of a handle A and a cup-shaped rubber B of elastic material secured to the face of said handle, substantially as and for the purpose herein 55 described.

2. A massage appliance consisting of a handle A and a cup-shaped rubber B of elastic material, ribbed on its concave face and secured to the face of said handle, substantially as and for the purpose herein described. 60

3. The massage appliance herein described, consisting of a pair of handles A A, a link C forming a universal-hinge connection between them and cup-shaped rubbers of elastic material mounted on the opposite faces of said handles. 65

4. The massage appliance herein described, consisting of a pair of handles A A, a link C forming a universal-hinge connection between them and cup-shaped rubbers of elastic material, ribbed on their concave faces and mounted on the opposite faces of said handles. 70

5. The combination of the handles A A; the link C forming a universal-hinge connection 75 between said handles and internally ribbed, cup-shaped rubbers B B, of elastic material on the opposite faces of the handles near their hinge connection, substantially as and for the purposes set forth.

TORSTEN SCHILLBERG.
